HIGHWAY CROSSING GATE

Edwin G. Little, Wilkinsburg, Pa., assignor to
The Union Switch & Signal Company, Swiss-
vale, Pa., a corporation of Pennsylvania

Original application October 5, 1938, Serial No.
233,437. Divided and this application August
29, 1939, Serial No. 292,430

2 Claims. (Cl. 39—7)

My invention relates to highway crossing gates.

One object of my invention is to provide a highway crossing gate of the type having a counterweighted gate arm biased to a lowered position and arranged to be moved to a raised or non-traffic obstructing position by a motor driven operating mechanism, in which the gate arm counterweight will be prevented from dropping suddenly and thereby causing damage to the operating mechanism, in the event that the gate arm becomes broken while it is in its lowered or traffic obstructing position.

Other objects and characteristic features of my invention will appear as the description proceeds.

The present application is a division of my copending application, Serial No. 233,437, filed on October 5, 1938 for Flexible coupling.

20 I shall describe one form of highway crossing gate embodying my invention, and shall then point out the novel features thereof in claims.

In the accompanying drawing, Figs. 1 and 2 are front elevational and top plan views, respectively, showing a highway crossing gate embodying my invention. Fig. 3 is an enlarged vertical sectional view of a coupling which is utilized for connecting the gate arm with the associated operating mechanism. Fig. 4 is a sectional view taken substantially on the line IV—IV of Fig. 3. Fig. 5 is a view showing the coupling member 12 in place on the shaft 10.

Similar reference characters refer to similar parts in each of the several views.

35 Referring first to Figs. 1 and 2, the reference character 1 designates a highway crossing gate arm, and the reference character 2 designates a mechanism for operating the gate arm 1. The gate arm 1 is of the type which is adapted to descend by gravity to its lowered or traffic obstructing position, and to be subsequently moved to its raised or non-traffic obstructing position by means of the operating mechanism, and as here illustrated it is secured to the outer end of an operating shaft 3 journaled in suitable bearings 4 mounted in a supporting bracket 5. The bracket 5, in turn, is secured in any suitable manner as by means of U-bolts 6 to a signal pole or mast 7, and is provided at the end opposite to the gate arm with a flange 8 to which the operating mechanism 2 is bolted. It will be seen, therefore, that the bracket 5 serves as a means for securing both the gate arm and the operating mechanism to the supporting pole 7. To pre-

vent the gate arm from developing excessive torque when it is descending, suitable counterweights 9 are provided in accordance with the usual practice.

The operating mechanism 2 may be of any 5 preferred type which, when energized, will move the gate arm against its bias to its raised position and hold it there, but which when deenergized will permit the gate arm to descend by gravity to its lowered position. As here shown, 10 this mechanism is similar to that shown and described in Letters Patent of the United States No. 1,138,087 granted to John P. Coleman on May 4, 1915, for a Railway signal, and inasmuch as this mechanism in itself forms no part of my 15 present invention, and is described in detail in the said Coleman patent, it is believed to be sufficient for purposes of the present disclosure to point out that this mechanism includes a main shaft 10 which is disposed in axial alignment 20 with the shaft 3, and which is connected with an electric motor not shown through suitable ratchet mechanism in such manner that when the motor is energized it will rotate the shaft 10 25 in a counterclockwise direction as viewed from the right in Fig. 3 through a sufficient angular distance to move the crossing arm from its lowered to its raised position, and that when the arm reaches its raised position the ratchet mechanism will permit the motor armature to 30 coast to a stop without shock. This mechanism also includes an electromagnet which becomes energized when the motor becomes energized, and which is effective when energized to hold the shaft 10 in any position to which it is rotated by the motor, but which when deenergized permits the shaft to rotate in the opposite direction from that which it is driven by the motor and to rotate the motor. The mechanism further includes suitable circuit controlling contacts for deenergizing the motor when the crossing arm reaches its full raised position without deenergizing the electromagnet, and for short-circuiting the motor to cause it to act as a brake when the motor is being driven by the descending gate arm.

The two shafts 10 and 3 are operatively connected to operatively connect the gate arm 1 with the operating mechanism 2 by means of a coupling which is disposed within a cylindrical 50 opening 11 formed in the rear wall of the operating mechanism 2. As shown in the drawing, the coupling comprises a main coupling member 12, a main coupling member 13 and two link members 14 and 15. The member 12 is provided 55

with a square hole 12a which receives the squared end 10a of the shaft 10 and with two diametrically opposite laterally projecting pins 12b and 12c, and is pinned to the shaft 10 by means of a 5 pin 16. The member 13 is similar to the member 12 and is provided with a square hole 13a which receives the squared end 3a of the shaft 3, and with two diametrically opposite laterally projecting pins 13b and 13c, and is secured to 10 the shaft 3 by means of a pin 17. The squared ends of the shafts 10 and 3 are so arranged that when these shafts occupy the proper relative operating positions, the four pins 12b, 13b, 12c and 13c will be disposed at the four corners of a 15 rectangle in the order named, as shown in Fig. 4.

The link member 14 comprises a central web portion 14a provided with two cam slots 14b and 14c which receive the pins 12b and 13c, respectively, of the two coupling members 12 and 13, 20 and an arcuate outer portion 14d to which a brake lining 18 of suitable friction material is fitted for cooperation with the wall of the opening 11. The link member 15 similarly comprises a central web portion 15a provided with two cam 25 slots 15b and 15c which receive the pins 12c and 13b, respectively, of the two coupling members 12 and 13, and an arcuate outer portion 15d to which a brake lining 19 of suitable friction material is fitted for cooperation with the wall of 30 the opening 11.

The operation of the gate is as follows: The cam slots in the two link members are so constructed and the parts are so proportioned that when the shaft 10 is rotated by the operating 35 mechanism in the proper direction to raise the gate arm 1, or the shaft 3 is rotated in the direction it is rotated when the gate arm is descending by gravity, the pins 12b, 13b, 12c and 13c will each cooperate with the associated cam slot 40 to force the links inwardly to the positions in which the brake linings are out of engagement with the wall of the opening 11, and it will be apparent, therefore, that when the motor is being operated to raise the gate arm, or the gate arm is 45 descending by gravity, the coupling will transmit torque directly from the one shaft to the other without any frictional force being exerted on either shaft due to the brake linings. If, however, a force is applied directly to the shaft 3 50 tending to rotate the shaft in the opposite direction from that in which it is rotated to lower the gate arm, as will be the case if someone attempts to raise the gate arm by hand, or if a vehicle collides with the gate when it is lowered and breaks 55 it off so that the counterweights 9 tend to drop suddenly, the pins 12b, 13b, 12c and 13c will then cooperate with the associated cam slots to force the links outwardly to the positions in which the brake linings 18 and 19 frictionally engage the

wall of the opening 11, and under these latter conditions the coupling will function to oppose the rotation of the shaft. The force exerted by the coupling under these latter conditions will depend upon the characteristics of the brake linings 5 used and the angles at which the cam slots are disposed in the two link members, and it will be apparent that by choosing the proper lining material and the proper cam angles the coupling can be made to act either as a positive lock against 10 rotation of the shaft 3 in one direction by a force applied directly thereto, or merely as a means for limiting the amount of force necessary to rotate this shaft, or as a means for limiting its rate of movement or both. In the latter case, the 15 crossing gate arm could be raised by hand in an emergency, although the braking effort exerted by the coupling would still be sufficient to retard the fall of the counterweight and thus prevent damage to the operating mechanism, in the event 20 that a car ran into the gate arm and broke it off.

Although I have herein shown and described only one form of crossing gate embodying my invention, it is understood that various changes and modifications may be made therein within 25 the scope of the appended claims without departing from the spirit and scope of my invention.

Having thus described my invention, what I 30 claim is:

1. In combination, a signal arm biased to a lowered position and provided with a counterweight, an operating mechanism for moving said arm to a raised position, and a coupling connecting said arm with said mechanism and including 35 means for preventing said counterweight from dropping in the event said arm becomes broken while in its lowered position.

2. In combination, a supporting post, a bracket secured to said post, an operating mechanism 40 secured to said bracket and provided in a wall adjacent to said bracket with a cylindrical opening and with a shaft extending into said opening, a second shaft journaled in said bracket and having one end extending into said opening in axial 45 alignment with said mechanism shaft, an arm secured to said second shaft and biased to a lowered position and partly counterbalanced by a counterweight, and a coupling disposed in said opening and including means for connecting said 50 mechanism shaft with said second shaft in such manner that movement of said arm to its lowered position will drive said mechanism shaft and that operation of said mechanism will move said arm to its raised position but that rotation of said 55 second shaft in a direction to move said arm to its raised position by means other than said mechanism is prevented.

EDWIN G. LITTLE.
